COMBINED CHURN AND WASHING MACHINE

Harvey A. Weichal, Kansas City, Mo.

Application January 13, 1934, Serial No. 706,567

1 Claim. (Cl. 259—75)

This invention relates to a combined churn and washing machine and has for an important object thereof the provision of a device which can be used with any suitable power means, particularly 5 a power means not operated by electricity.

Another object of this invention is to provide in a combination device of this kind a novel tub supporting and oscillating means which is so constructed that the tub may be readily removed 10 therefrom and another tub inserted in the supporting means, there being one type of tub for use in churning of liquids and another type for use in washing garments or the like.

A further object of this invention is to provide 15 an exceedingly simple structure of this kind which is constructed in a manner whereby it may be readily moved from place to place so that it may be readily transported to the place at which the operation is to be performed.

The above and various other objects and advantages of this invention will in part be described and in part be understood from the following detailed description of the present preferred embodiment, the same being illustrated in the accompanying drawings wherein:—

Figure 1 is a detail side elevation of a device constructed in accordance with the preferred embodiment of this invention.

Figure 2 is a detail front elevation of the device 30 partly broken away and in section.

Figure 3 is a transverse section taken through the tub structure shown in Figures 1 and 2.

Figure 4 is a detail end elevation partly broken away and in section of a modified form of tub 35 structure.

Figure 5 is an enlarged sectional view taken on the line 5—5 of Figure 2.

Referring to the drawings wherein like characters of reference designate corresponding parts 40 throughout the several views, the numeral 10 designates a base which has mounted thereon a power member P of suitable character which is provided with an eccentric 11. The base 10 has disposed thereon at a point spaced from the power member P, a pair of uprights or standards 12 and 13, which are spaced apart the desired distance. A substantially U-shaped tub supporting member, generally designated as 14, which is provided on each free leg thereof with out-turned 45 trunnions 15, is journaled or rockably mounted 50 on the standards or posts 12 and 13, by means of a bearing structure 16, which engages the trunnions 15. The bight 17 of the tub supporting member 14 has an offset central portion 18 which 55 is engaged by one end of a pitman 19, the pitman

19 being connected at the other end to the eccentric 11.

As shown in Figures 1 and 2, a tub structure T is supported by the tub supporting member 14, and this tub structure T comprises a casing 20 of suitable configuration which is provided at each end thereof with a pair of outstanding lugs 21 provided in the outer side thereof with elongated grooves 22. The parallel legs 23 of the tub supporting member 14 are adapted to engage in the 10 grooves 22 of the lugs 21.

A pair of handles 24 are secured one at each end of the tub T so as to facilitate the placement or removal of the tub T from the supporting member 14. A lid L is hinged to the tub T 15 and may be locked in closed position by means of pivoted members 25. In the present instance, the tub T constitutes a churn which has on the interior thereof a perforated baffle B releasably engaged between pairs of guides 26 carried by 20 the ends 27 of the tub T. Each end 27 has a pair of guides 26 on the inside thereof.

In Figure 4, there is shown a tub structure T' which is used in the washing of clothes. This tub structure T' has a ribbed or corrugated inner 25 surface 28 and is provided at each end thereof with outstanding lugs 21' which are grooved after the manner of the lugs 21 and are releasably engaged with the tub supporting member 14. This tub T' has a lid L' hinged thereto and 30 pivoted locking members 25' are carried by the tub T' so as to releasably lock the lid L' in closed position.

A wringer supporting member, generally designated as 29, is hinged or pivoted to one of the vertical standards and in the present instance is hinged to the standard 12, as at 30. The wringer supporting member 29 comprises a vertically extending post or support 31 and a horizontally disposed bar 32 secured to the upper end 40 of the post 31. The wringer supporting member 29 is releasably locked in operative position by means of a pin 33 carried by the post 31 which engages in an opening provided in a yieldable locking member 34 carried by the post 12. When 45 the wringer supporting member 29 is in operative position, the wringer engaging member or bar 32 is disposed in a position extending outwardly of the base 10 and when in inoperative position, is disposed with the wringer engaging 50 member 32 extending inwardly of the base.

In the use and operation of the combined churn and wringer herein disclosed, when it is desired to churn liquids such as milk, the tub structure T is mounted between the parallel arms 23 of the 55

supporting member 14. The power member P is then set in operation and the pitman 19 will oscillate the tub T for the desired length of time.

When it is desired to wash clothes or the like, the tub T may be removed by withdrawing the tub T vertically from the supporting member 14, whereupon the tub structure T' used for washing clothes is disposed between the arms 23. At this time, the wringer supporting member 29 may be swung with the horizontal wringer engaging member 32 projecting outwardly of the base 10 and the desired hand operated wringer may be clamped onto the support 32.

It will be apparent from the foregoing that an exceedingly simple structure has been provided which can be used for either churning of liquids or can be used in the washing of clothes and that any suitable form of power member P may be used to operate the device. This power member P may be in the form of an electric motor, an internal combustion engine or a spring operated power member, it being obvious that the power member P will be of a character suitable to the purchaser of the device.

It is, of course, understood that various changes and modifications may be made in the details of construction and design of the above specifically described embodiment of this invention without departing from the spirit thereof, such changes and modifications being restricted only by the scope of the following claim.

What is claimed is:—

In a device of the character described including a support, bearing members on the support, a tub having slots in its opposite ends, a cylindrical member bent upon itself to constitute an oscillatory supporting frame, said frame including guide rail portions for engaging said slots in the tub, out-turned trunnions at the upper ends of said guide rail portions pivotally engaging said bearings, a horizontal portion for supporting said tub in proper axial relation with said trunnions and an offset in said horizontal portion constituting a journal whereby said frame may be connected for oscillation by a suitable source of power.

HARVEY A. WEICHAL.
